UNITED STATES PATENT OFFICE

AUGUST SCHWARZ, OF CHICAGO, ILLINOIS

PROPELLER

Application filed October 20, 1930. Serial No. 489,916.

This invention relates to improvements in propellers and more particularly to improvements in the propeller inventions set forth in my co-pending applications, Serial Nos. 432,733 and 481,153. The present invention is designed for use upon air craft, water craft, and may be applied to vehicles generally.

One object is to provide a propeller having novel wing or blade adjustment whereby the angle of the blades to the frame may be altered as desired thus providing means for effecting a gradual landing, a gradual ascent, or a forward or reverse movement of the vehicle while the motors run constantly in one direction. When applied to a steam ship with turbines, no reverse turbines will be required.

A still further object is to provide a propeller having adjustable blades, the blades being simultaneously adjustable either by manual manipulation or by power, the adjustment being smooth, gradual and frictionless.

A still further object is to provide a propeller wherein the blades are readily adjustable while the vehicle is in motion thus affording the vehicle great mobility, enabling it to take advantage of sudden changes in the wind and greatly facilitating its control.

With the foregoing and other objects in view the invention consists in the combination and arrangement of parts to be herein-after fully described, pointed out in the claims and illustrated in the accompanying drawings which form a part of this application for patent and in which—

Fig. 1 is a top plan view, partly in section, of the propeller.

Fig. 2 is a cross sectional view taken on the line 2—2 of Fig. 1.

Fig. 3 is an enlarged detail view of the adjusting shaft lock.

Fig. 4 is a cross sectional view taken on the line 4—4 of Fig. 1.

Fig. 5 is an enlarged fragmentary sectional view through the motor shaft and slidably blade control mechanism mounted thereto.

Fig. 6 is a fragmentary view partly in plan and partly in section, of a slightly modified form wherein hydraulic power is used to

actuate the blade controls, the pistons being shown at the end of their forward stroke.

Fig. 7 is an enlarged fragmentary sectional view through the propeller frame showing a blade mounting.

Fig. 8 is a cross sectional view taken on the line 8—8 of Fig. 7.

Fig. 9 is an enlarged fragmentary sectional view of Fig. 1 illustrating the connection between the blades and the adjusting plate therefor.

Like reference characters denote corresponding parts throughout the several views.

The reference numeral 1 denotes the motor bearing and 2 the motor shaft, the latter being formed with a plurality of longitudinal key ways 3 to permit the sleeve 4 to be keyed thereto so that it may rotate with said shaft while being slidably longitudinally thereof, said sleeve being formed with a plurality of spaced annular ribs 5 that fit into corresponding recesses in the bearing 6 disposed upon said sleeve so that the latter may be free to rotate independently of said bearing.

The sleeve 4 extends transversely of and beyond said bearing 6 and at one end has fast thereto or integral therewith the annular plate 7 of greater diameter than said bearing. Fast upon the outer end of the motor shaft 2 is the hub 8 which is connected by spoke-blades 9 to the annular frame 10 that carries the blades 11, preferably four in number, although any number of blades may be employed. Each blade 11 is mounted in the frame 10 for rotary adjustment, a reduced blade portion extending through a perforation 12 and being provided with an integral key 13 that rests upon the ring 14 encircling the reduced blade portion, said portion being threaded throughout a portion of its length to receive the lock nut 15, a reduced portion 16 being square in cross section and reduced at its inner extremity to permit it to be fitted in the hub 8.

In certain adaptations of the propeller the spoke-blades 9 are eliminated as unnecessary on account of the blade inner-portions serving as spokes. Keyed to the reduced portion 16 of each blade is an arm or link 17 con-

nected by ball and socket joint to an intermediate link 18 that is likewise connected to a stud 19 secured to the annulus 7.

Referring now to all figures of the drawings except Fig. 6, the bearing 6 is connected by clamps or arms 20 to interiorly threaded sleeves 21 that telescopically receive and mesh with the threaded portions 22 of the rotary shafts 23 received in the friction bearings 24 connected by straps 25 to the motor bearing 1. Fast upon each shaft 23 is a sprocket wheel 26, said wheels being connected together by a sprocket chain 27.

Fast upon one shaft 23 is a gear wheel 28 in mesh with a similar wheel 29 fast upon the control shaft 30 journaled in bearings 31 provided at one end with the operating hand wheel 32. A clamp 33 supported by bracket 34 receives the shaft 30 and is provided with a handle 35 whereby it may be caused to grip the shaft to lock it against rotary movement when desired.

Referring now to Fig. 6, the arms 20 carry sleeves 21 that receive the piston rods 36 that extend through cylinders 37 and are provided with pistons 38 operated by hydraulic pressure, the liquid passage through the pipes 39, 40 thus providing hydraulic pressure to operate the type propeller herein shown. When the piston 38 is at the center of the cylinder 37 the blades are in neutral position. When the pistons are in the position shown the blades are positioned for forward speed. When the pistons are at the opposite or lower ends of the cylinders the blades are positioned for reverse movement.

In operation, rotation of the hand wheel 32, Fig. 1, will rotate shaft 30 and through gear wheels 29, 28 rotate one shaft 23 which, through the medium of sprocket wheels 26 and sprocket chain 27 will rotate the other shaft 23 thus causing the sleeves 21 to travel thereover, moving the bearing 6 and sleeve 4 longitudinally of the motor shaft 2, together with the annulus 7 thus causing the stud 19 and arms 18, 17 to oscillate the blades in the frame 10 to adjust the same to any angle with the frame desired. In Fig. 8 the position of the blades with relation to the frame is shown when the machine is at rest. When the take-off is made the blades are turned slightly so that the position of the key 13 will be altered somewhat.

When full speed forward is desired the blades are adjusted to as great an angle to the frame as possible, or until the keys 13 of the blades ride against the keys 13' of the frame thus relieving the pressure in the friction bearing. The blades can be adjusted forward or backward depending upon the direction of movement desired. The blade adjustment may be such as to cause the blades to impart a forward or pulling power to move the vehicle forward, or a reverse impulse to move the vehicle backward. A slow landing

can be effected by disposing the blades at such an angle as to cause a reverse while the craft is moving forward. This would provide a braking action, quickly slowing up the movement of the craft.

When the propeller is used in water craft it is positioned at the rear while when in use upon airplanes or hydro-planes it is positioned either at the rear or at the front. The operation of the form shown in Fig. 6 is the same as that described except that the shafts 36 are actuated by hydraulic pressure. The bearing 6, sleeve 4 and motor shaft 2 are lubricated by oil through the oil pipe 41. In the case of water craft where the form shown in Fig. 6 is used the friction bearing 6 is placed outside the craft and the shafts 36 extend through the hull into the interior.

What is claimed is:

1. In a propeller of the class described having a plurality of blades rotatably supported in a frame, which is rigidly mounted on a solid shaft having a plurality of keyways therein, a sleeve slidable on said propeller shaft, but prevented from rotary movement relative to said shaft, a bearing adapted to receive said sleeve, cooperating means on said sleeve and in said bearing for permitting rotary movement of the keyed-together shaft and sleeve relative to the bearing, but preventing axial movement of the sleeve relative to the bearing, a pair of levers for each propeller blade, each pair of levers pivotally joined together, the other end of one of said levers being rigidly fastened to the corresponding propeller blade, the free end of the other lever of each pair pivotally connected with the sleeve, and means for axially moving the bearing and the sleeve on the solid propeller shaft and thereby adjust the angularity of the propeller blades.

2. In a propeller of the class described, a shaft, a frame fixed thereon transversely of the axis of the shaft, a plurality of blades journaled in the said frame for oscillatory movements therein, a sleeve splined upon the said shaft, a bearing in which the sleeve and its shaft are mounted for rotation, the said bearing and sleeve having interengaging means effecting joint axial movement of the same, a radial arm fixed to each propeller blade, a link pivotally connecting the said arm with the sleeve, and means for moving the sleeve and its bearing longitudinally upon the shaft to adjust the angularity of the propeller blades.

3. In a propeller of the class described, a shaft, a frame fixed thereon transversely of the axis of the shaft, a plurality of blades journaled in the said frame for oscillatory movements therein, a sleeve splined upon the said shaft, and provided with an annular plate, a bearing in which the sleeve and its shaft are mounted for rotation, the said bear-

- ing and sleeve having interengaging means effecting joint axial movement of the same, a radial arm fixed to each propeller blade, a link pivotally connecting the said arm with the sleeve through the annular plate, and means for moving the sleeve and its bearing longitudinally upon the shaft to adjust the angularity of the propeller blades. 5
4. In a propeller of the class described, a shaft, a frame fixed thereon transversely of the axis of the shaft, a plurality of propeller blades journaled in the said frame for oscillatory movements therein, a sleeve splined upon the shaft and provided at the end adjacent the said frame with an annular plate, a bearing in which the sleeve and its shaft are mounted for rotation, the said bearing and sleeve having interengaging annular ribs and recesses to effect joint axial movement of the same, a radial arm fixed to each propeller blade, a link pivotally connecting the said arm with the sleeve, and means for moving the sleeve and its bearing longitudinally upon the shaft to adjust the angularity of the propeller blades. 15
5. In a propeller of the class described, a shaft, a frame fixed thereon transversely of the axis of the shaft, a plurality of propeller blades journaled in the said frame for oscillatory movements therein, a sleeve splined upon the said shaft and provided at the end adjacent the said frame with an annular plate, a bearing in which the sleeve and its shaft are mounted for rotation, the said bearing and sleeve having interengaging means to effect joint axial movement of the same, a radial arm fixed to each propeller blade, a link pivotally connecting the said arm with the sleeve through the annular plate, and screw-operated means for moving the sleeve and its bearing longitudinally upon the shaft to adjust the angularity of the propeller blades. 20
6. In a propeller of the class described, a shaft, a frame fixed thereon transversely of the axis of the shaft, a plurality of propeller blades journaled in the said frame for oscillatory movements therein, a sleeve splined upon the shaft and provided at the end adjacent the said frame with an annular plate, a bearing in which the sleeve and its shaft are mounted for rotation, the said bearing and sleeve having interengaging means to effect joint axial movement of the same, a radial arm fixed to each propeller blade, a link pivotally connecting the said arm with the sleeve through the annular plate, and fluid pressure means for moving the sleeve and its bearing longitudinally upon the shaft to adjust the angularity of the propeller blades. 25
7. In a propeller of the class described, a shaft, a frame fixed at its hub transversely upon the said shaft, a plurality of radial blades journaled in the said frame for oscillatory movements therein, the inner end of the shaft of each blade having a bearing in
- the hub, an arm attached to the blade shaft at a point between the frame and its hub, and means for moving the said arm to adjust the angularity of the propeller blade. 30
8. In a propeller of the class described, a shaft, a frame fixed at its hub transversely of the axle of the shaft, a plurality of radial blades journaled in the said frame and its hub for oscillatory movements therein, a sleeve splined upon the said shaft, a bearing in which the sleeve and its shaft are mounted for rotation, the said bearing and sleeve having interengaging means effecting joint axial movement of the same, a radial arm fixed to each propeller blade at a point intermediate to frame and its hub, a link pivotally connecting the said arm with the sleeve, and means for moving the sleeve and its bearing longitudinally on the shaft to adjust the angularity of the propeller blades. 35
- In testimony that I claim the foregoing as my own I have hereto affixed my signature.
- AUGUST SCHWARZ.
